US00D851878S

(12) United States Design Patent (10) Patent No.: US D851,878 S
Pauk (45) Date of Patent: * Jun. 25, 2019

(54) SHOE

(71) Applicant: NIKE, Inc., Beaverton, OR (US)

(72) Inventor: Matthew R. Pauk, Portland, OR (US)

(73) Assignee: NIKE, Inc., Beaverton, OR (US)

() Term: 15 Years

(21) Appl. No.: 29/656,081

(22) Filed: Jul. 10, 2018

(51) LOC (11) Cl. 02-04

(52) U.S. Cl.

USPC D2/947

(74) Attorney, Agent, or Firm — Banner & Witcoff, Ltd.

(57) CLAIM

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is a rear view thereof; and,

FIG. 5 is an opposite side view thereof.

The broken lines depicting the remainder of the shoe show features that form no part of the claimed design.

1 Claim, 5 Drawing Sheets
